AUXILIARY HANDLE MEANS FOR ELECTRIC HAIR CLIPPERS

Arthur W. Dreser, Box 598, Rte. 6, Sappington, Mo.

Filed Nov. 9, 1959, Ser. No. 851,784

7 Claims. (Cl. 30—210)

The present invention relates generally to electric hair clippers, and more particularly to the provision of means on conventional clippers of this type adapted to enable individuals to cut and trim their own hair without assistance from another or others.

Stated more specifically, the present invention provides means adapted to facilitate the cutting and trimming of a person's own hair with a conventional electric clipper. Heretofore, there has been no problem with respect to the front and side hair growth, but what may be termed a self-administered "full" haircut has not been possible, insofar as I am aware.

In accordance with the concepts of the present invention, auxiliary handle means are provided whereby an individual with the aid of a stationary mirror and a hand mirror may cut and trim the hair on the rear of his head and neck in the privacy of his home, and impart thereto the appearance of having been done by a professional barber.

The attainment of this result is facilitated by the provision of a pair of removable handle bars that may be embodied in conventional clipper constructions without in any way changing their normal operational mechanisms.

As a general rule clipper casings of the type under consideration are molded of plastic material and split transversely from end to end to provide a mechanism containing housing, and a cover member therefor that is removably secured thereto by screws, as is understood.

In ordinary use, this casing is manipulated by holding the incorporated handle portion thereof in the hand of an operator, and directing the reciprocal toothed blade clipping arrangement into engagement with the hair in well understood barbershop technique.

Many men with a little practice have attained proficiency in the employment of electrical hair clippers insofar as the trimming of sideburns and top of the head hair are concerned. Insofar as I am aware however, the present invention provides the first means to enable a man to cut and trim the hair on the neck and back of his own head.

In accordance with the teachings of the present invention, the handle means under consideration may be embodied in any conventional electric clipper so as to render it effective for the purpose in contemplation.

Accordingly, the primary objective of this invention is to secure to, or embody in the casing of conventional clippers of the electric type, handle means whereby with the aid of a stationary mirror and a hand mirror, a man may quickly and efficiently "give himself a haircut."

In the attainment of this objective, it would obviously be requisite that directional control of the clipper be had. In order to provide such control in a most efficient manner, the present invention provides a pair of projecting handle bars or grip members that extend laterally beyond each side of the clipper casing, so that the disposition of the cutting blades relatively to the hair may be controlled

2

alternatively by the right or the left hand of the person employing the clipper in this novel function.

As a general rule, clippers of the type under consideration have casings that are approximately two inches in width. The present invention contemplates providing such casings with transversely extending handle arrangements that measure approximately twelve inches from end to end. Thus the manually engageable handle bar members projecting laterally from each side of the casing 10 would generally be about five inches in length.

Preferably but not necessarily, the contemplated handle bars would be round in cross-section, and molded of plastic material. Projecting from one end of each handle bar and having a smaller diameter relatively thereto is a 15 threaded extension integrally molded therewith. These extensions are adaptable to threaded internally threaded or tapped sockets provided therefor on the clipper casing in accordance with the teachings of this invention.

A feature of the invention is that no change whatever is requisite in the internal construction and other mechanism of conventional clippers. In one form of the invention, the sockets aforesaid are provided in a generally cylindrical element of plastic material that is secured atop 20 the cover of the clipper casing. A recess is formed in what will be termed the undersurface of said element, a pair of tapped openings are drilled in the cover member, and said cylindrical element is secured thereto preferably by means of screws, although it will be understood that 25 said element may be bonded to the cover by other means, such as cement and so on.

With the cylindrical socket equipped element permanently incorporated, the two handle members may be applied for the purpose contemplated, and thereafter removed if desired, as will appear.

In another example, the internally threaded sockets for the reception of the threaded extensions of the handles are provided in an upstanding transversely extending boss portion that is molded into the cover member of the casing, 35 as will appear.

Alternatively, the present invention contemplates an arrangement wherein the internally threaded sockets are provided in laterally projecting bosses integrally formed in the mechanism enclosing housing proper, rather than 40 in the cover member therefor.

It is therefore also an object of the present invention to provide auxiliary handle means in such manner that incorporation thereof in conventional clippers may be had without effecting the operational mechanisms thereof.

50 A further object is to provide the means aforesaid in removable form, so that as will appear, the clipper may be conveniently packed for shipping or for travel purposes.

The invention is illustrated on a sheet of drawings that 55 accompanies this specification, and a more comprehensive understanding of its novel objectives and advantages may be had from the detailed description to follow with reference to said drawings wherein:

Figure 1 is a top plan view of a conventional electric 60 hair clipper (shown partly in broken lines), embodying auxiliary handle means in accordance with the concepts of my invention;

Figure 2 is a similar view, partly in horizontal section, 65 particularly illustrating the removability of the auxiliary handle bars.

Figure 3 is a transverse sectional view on an enlarged scale, taken substantially along the line 3—3 of Figure 1;

Figure 4 is a fragmentary top plan view of a conventional electric hair clipper incorporating a modified auxiliary handle means in accordance with the concepts of my 70 invention;

Figure 5 is a transverse sectional view on an enlarged scale, taken substantially along the line 5—5 of Figure 4;

Figure 6 is a fragmentary top plan view of a conventional electric hair clipper incorporating auxiliary handle means in association with the casing housing instead of the cover member thereof;

Figure 7 is a fragmentary side elevational view of the clipper shown in Figure 6, said view being partly in section and on an enlarged scale, taken on the line 7—7 of Figure 6; and

Figure 8 is a pictorial presentation of the manner wherein an individual would employ the present invention in use.

A somewhat schematically outlined conventional electric hair clipper of the type under consideration is generally designated A wherever it appears in the drawings, either in its entirety or fragmentarily.

Inasmuch as the present invention concerns only the operating mechanism enclosing housing B and the cover member C therefor, these have been presented in full lines, whereas except in Figure 8, the reciprocal toothed blade cutting assembly D and the electrical connections E of the clipper A have been presented in broken lines. Usually, the cover members C are removably secured to the housings B by means of a plurality of screws such as those designated s. That portion of the clipper comprised of the united cover and housing components that is remote from the cutting assembly D is usually tapered or reduced in width as shown, and constitutes the handle wherewith the clipper would ordinarily be manipulated, as is well understood.

A simple form of my invention is depicted in Figures 1 through 3. In this embodiment, the auxiliary handle means comprises an assembly of three generally cylindrical elements preferably molded of plastic material. Included in this assembly is a cylinder 10 having an internally threaded socket 12 formed in each end thereof. What will be termed the underside of the cylinder 10 has formed therein a recess 14, the length of said recess being appropriate for the reception of the top portion of the cover member C.

A pair of transversely spaced holes 16 is provided in the cylinder 10 for the passage therethrough of screws 18 into correspondingly spaced tapped openings 19 in the cover member C. Preferably as shown, but not necessarily, the holes 16 are countersunk, so that the heads of the screws 18 will lie flush or slightly below the top surface of the cylinder 10.

Preferably as shown, the handle bars 20 are of cylindrical form and of a diameter corresponding to that of the cylinder 10. Each handle bar 20 is provided at one end with a threaded extension 22 of reduced diameter. The external diameters of these extensions correspond to the internal diameters of the sockets 12, and the length of them is slightly less than the depth of said sockets. At the mergence of each extension into the main body of the handle bar 20, an annular shoulder 24 results, said shoulders serving to limit inward movement of the handle bars when the latter are mounted.

From the foregoing it should be clear that in order to equip a conventional clipper casing with the auxiliary handle means of my invention, the only operation necessary with respect to said casing is to provide the transversely spaced tapped openings 19 in the cover C, the spacing of said openings of course being determined by the spacing of the holes 16 in the socket cylinder 10.

In the embodiment of the invention illustrated in Figures 4 and 5, the internally threaded sockets 12 are formed in the opposed end portions of an upwardly projecting boss 26 integrally molded with the cover C of the clipper casing. Preferably the boss portion 26 is arcuately contoured and extends atop the cover from side to side thereof as shown.

In the embodiment of the invention illustrated in Figures 6 and 7, the internally threaded sockets 12 are

formed in opposed preferably circular bosses 28 that are integrally molded with the housing B of the clipper casing, and project laterally therefrom.

In view of the foregoing, it should be manifest that the invention is a simple one, and is characterized by the provision of a pair of opposed internally threaded sockets on the clipper casing, and a pair of handle bars having externally threaded extensions whereby said handle bars may be removably integrated with said casing.

10 The manner wherein a clipper embodying the present invention may be employed in the attainment of its objectives is pictorially presented in Figure 8. It will be understood that the individual shown manipulating the clipper with his right hand and a hand mirror m with his left, would have a comparatively larger stationary mirror (not shown) disposed at his back. Following completion of the self-administered cutting and trimming operation with respect to the right side of his head, the individual would simply transfer the mirror m to his right hand, and manipulate the clipper with his left hand to thus complete a self-administered haircut and trim operation.

What I claim is:

1. In an electric hair clipper including a casing incorporating a handle portion for manipulating the clipper in the customary manner: the combination with the casing of a pair of removable auxiliary handle bars each projecting laterally from one side of said casing for manipulating the clipper during hair cutting and trimming operations self-administered by an individual to the neck and back

30 of his head.

2. In combination with a hair clipper of the electric type including a casing comprised of an operating mechanism enclosing housing and a removable cover therefor: auxiliary handle means removably secured to said casing whereby to facilitate manipulations of the clipper in self-administered hair cutting and trimming operations of the character described.

35 3. In combination with a hair clipper of the electric type including a casing comprised of an operating mechanism enclosing housing and a removable cover therefor: auxiliary handle means removably secured to said casing whereby to facilitate manipulations of the clipper in self-administered hair cutting and trimming operations of the character described, said means including a cylinder rigidly secured to said cover and extending transversely across the top thereof, an internally threaded socket formed in each end portion of the cylinder, a pair of cylindrical handle bars, and a threaded extension of reduced diameter relatively thereto projecting from one end of each handle bar for engagement with one of said sockets.

40 4. In combination with a hair clipper of the electric type including a casing comprised of an operating mechanism enclosing housing and a removable cover therefor: auxiliary handle means removably secured to said casing whereby to facilitate manipulations of the clipper in self-administered hair cutting and trimming operations of the character described, said means including a cylinder element rigidly secured to said cover and extending transversely across the top thereof, an internally threaded socket formed in each end portion of the cylinder element, a pair of handle bars, a threaded extension of reduced diameter relatively thereto projecting from one end of each handle bar and being adapted to engage in one of said sockets, and an annular shoulder formed in the handle bar by the mergence of said extension therewith, said shoulder being adapted to engage against an end face of the cylinder element aforesaid when the handle bar is in position.

45 5. The structure set forth in claim 4, wherein the cylinder element is provided with an appropriate recess in its undersurface for the reception of the upper surface of the cover; wherein the handle bars are cylindrical and are diametered correspondingly to said cylinder element; wherein the cylindrical section has formed therein

50 60 65 70 75 80 85 90 95

a pair of spaced holes; and wherein the cover member has formed therein a pair of tapped holes spaced correspondingly to the holes in the cylindrical section, whereby screws passing through the last named holes into engagement with the tapped holes in the cover member serve to rigidly maintain the cylinder element aforesaid rigidly in position on said cover.

6. In combination with a hair clipper of the electric type including a casing comprised of an operating mechanism enclosing housing and a cover therefor: auxiliary handle means wherewith to manipulate the clipper in self-administered hair cutting and trimming operations of the character described, said means comprising an upstanding arcuate boss portion integrally formed with said cover and extending transversely from side to side thereof, a threaded socket formed in each end of said boss portion, a pair of cylindrical handle bars each having a threaded extension of reduced diameter relatively thereto projecting from one end thereof, the diameters of said extension and said sockets being in correspondence, and an annular shoulder formed in each handle bar

by the mergence of said reduced extension therewith, said shoulder being adapted to engage against said boss portion when the handle bar is in position.

7. In combination with a hair clipper of the electric type including a casing comprised of an operating mechanism enclosing housing and a cover therefor: auxiliary handle means wherewith to manipulate the clipper in self-administered hair cutting and trimming operations of the character described, said means comprising a pair of bosses in transverse alignment each projecting from one side of said housing and molded integrally therewith; a threaded socket formed in each boss, a pair of cylindrical handle bars each having a threaded extension of reduced diameter relatively thereto projecting from one end thereof, the diameters of said extension and said sockets being in correspondence, and an annular shoulder formed in each handle bar by the mergence of said reduced extension therewith, said shoulder being adapted to engage against said boss portion when the handle bar 20 is in position.
